RADIOPHONE COMMUNICATION SYSTEM

William J. Schnell, Berwyn, Ill., assignor to Electrical Research Laboratories, Inc., Chicago, Ill., a corporation of Illinois

Application August 6, 1937, Serial No. 157,787

18 Claims. (Cl. 179—1)

This invention relates to a combined radio receiver and telephonic system.

An object of this invention is to provide a communication system in which a radio receiver, comprising the usual reproducer, and a remotely positioned reproducer may be selectively controlled to permit two-way telephonic communication between the receiver and the remotely positioned reproducer.

Another object of the invention is to provide means by which a radio receiver may be selectively controlled to transmit radio signals to a remotely positioned reproducer and to establish telephonic communication between persons at the receiver and persons at the remote point.

Another object of the invention is to provide, in connection with the above stated system, means by which a calling signal may be transmitted from the remote point to the radio receiver.

Another object of the invention resides in the provision of a control unit readily connectable to substantially any radio receiver and to a remotely positioned reproducer by which said receiver and reproducer may be adapted for telephonic communication between remote points, which control unit shall be simple, compact in construction, efficient in operation and inexpensive in cost.

Other and further objects and advantages of the invention will be apparent from the following description when taken in connection with the accompanying drawings, wherein:

Fig. 1 is a view in perspective of the units forming a combined radio receiver and telephonic communication system in accordance with applicant's invention.

Fig. 2 is a schematic representation of the electric connections of the external units.

Fig. 3 is a diagrammatic view in perspective of a control switch forming a part of the control unit.

Fig. 4 is a perspective view of a call signal control switch forming a part of the invention.

As shown in Fig. 1, the invention comprises a radio receiver 2 of any suitable conventional structure; a sound reproducer or loudspeaker 4 normally forming a part of such receiver and which, as hereinafter to be described, is also employed as a transmitter or microphone; a remotely positioned sound reproducer or loudspeaker 6, which similarly is also employed as a transmitter or microphone; a calling device or buzzer 8; and a control switch 10 therefor associated with the reproducer-microphone 6; and

a control unit 12 preferably adjacent the radio receiver 2.

The control unit 12 comprises a housing 14, on the front panel of which is mounted a suitable strip 16 carrying functional indicia representing the condition of the system for different settings of a manually operable knob 18 and pointer 20. Such indicia carrying strip 16 may, for example, comprise a sector 22 marked "Radio", a sector 24 marked "Listen", and a sector 26 marked "Talk", indicating that when the pointer faces the sector 22 the system is adjusted for the reception of radio signals; that when the pointer faces the sector 24 the system is adjusted for transmission of messages from the remote point 15 to the receiver; and that when the pointer faces the sector 26 the system is adjusted for transmission of messages from the control station to the remote point.

The manually operable knob 18 and pointer 20 are carried on the projecting end of a shaft 28 (Fig. 3) of a switch means 30. The shaft 28 passes through the front panel of the housing 14 and is rotatably supported in suitable brackets (not shown) within said housing. The control unit 14 comprises, in addition to the elements described, connecting means or cables 32, 34 and 36 and a socket 38. The cable 32 is connected at one end to the control unit and at its other end to a plug 40 adapted to be inserted into the usual socket 42 provided for the reception of the speaker plug. The cable 34 is also connected at one end to the control unit and carries at its other end suitable connecting plugs or tip jacks 44 and 46 adapted to be inserted into suitable sockets 48 and 50 secured to the chassis of the radio receiver and connected in the circuit of the latter in a manner later to be described. The cable 36 is likewise connected at one end to the control unit 14 and at its other end to the remotely positioned reproducer-microphone 6. If desired, the cable 36 may terminate in a suitable socket adapted to detachably receive the usual connecting plug associated with a loudspeaker.

The socket 38 is adapted to receive the usual speaker plug carried on the free end of the connecting cable 52 of the speaker or reproducer-microphone 4.

On the walls of the housing for the reproducer-microphone 6, or on a separate support 50 associated therewith, is mounted in any desired manner the calling device or buzzer 8 and a battery or set of batteries 54, as for example, a pair of flash light batteries, energizing the buzzer 8. The buzzer 8 may be of any desired type, for 55

example of a kind adapted to operate at the low voltage provided by a pair of small flash light batteries connected in series.

The switch 10 may be of any conventional structure providing a simultaneously operable single-pole, double-throw switch element and a single-pole, single-throw switch element. As shown in Fig. 4, the switch 10 selected for illustration comprises a pair of movable contact blades 56 and 58, the blade 56 being adapted selectively to engage fixed contacts 60 and 62, and the blade 58 being adapted to engage a fixed contact 64 when the blade 56 engages the fixed contact 62. Suitable insulating blocks 66 are provided between each of the fixed and movable contacts.

The operating means for the switch 10 may comprise a push button 68 slidably supported in one wall of the speaker housing or other supporting plate, the blades 56 and 58 by reason of their resiliency normally retaining the button 68 in its extended position—in which position the blade 56 engages the contact 60 but the blade 58 is out of engagement with the contact 64.

The switching means 30 controlled by the shaft 28 of the control unit 12 comprises, in the illustrative embodiment, nine movable contacts 70 to 86, with each of which is associated a group of fixed contacts. The movable contacts 70 to 86 may be secured to the face of an insulating disk 88 adjacent the periphery thereof and angularly disposed as shown in Fig. 3. The insulating disk 88 is secured to the shaft 28 for rotation therewith.

The three groups of fixed contacts comprising nine contacts 90 to 106 may be mounted on an insulating disk 108 supported by spaced rods 110 and 112, which rods may be supported in any suitable manner (not shown) within the housing 14. The three movable contacts 76, 78 and 80 are similarly mounted on an insulating disk 114 secured to the shaft 28 for rotation therewith, and the three groups of fixed contacts comprising contacts 116 to 132 associated with said movable contacts may be mounted on an insulating disk 134 also supported on the rods 110 and 112.

The three movable contacts 82, 84 and 86 are likewise mounted on an insulating disk 136 secured to the shaft 28 for rotation therewith and the three groups of contacts comprising nine contacts 138 to 154 are mounted on a disk 156 similarly supported by the rods 110 and 112.

It should be noted that the movable contacts are simultaneously operable to engage their corresponding first, second or third fixed contacts, and that the switch means 30 therefore comprises in substance nine single-pole, triple-throw switches simultaneously operated to the corresponding positions by the shaft 28 and manually operable knob 18.

Means are provided for normally retaining the shaft 28 and each of the movable contacts in the positions shown in Figs. 1 and 3 wherein each of the movable contacts engages the first contact of its group of three contacts and wherein the pointer 20 is alined with the "Radio" sector 22. This means comprises a lever 158 secured to the inner end of the shaft 28 and a spring 160 secured to the outer end of the lever 158 and to a suitable pin carried by a lug 162 formed on or secured to the base of the housing 14. It will be evident that the spring 160 moves the shaft 28 in a counterclockwise direction, as seen in

Fig. 3, and normally retains the switches in the positions shown in said figure.

In Fig. 2 are schematically illustrated the connections between the switch means 30 of the control unit 12 and the other units of the system. Certain of the circuits of the radio receiver are schematically represented in said figure for the purpose of showing the connections of the control unit to said receiver.

As shown in said figure, the circuits of the radio 10 receiver comprise a detector 164, the input of which is connected in the conventional manner to the usual high frequency amplifier, which in turn is connected to a suitable antenna. The coupling between the detector 164 and the tube 166 forming the first stage of amplification of the audio-amplifier comprises a volume control resistor or potentiometer 168 grounded as at 170 and adjustably connected by the lead 172 to the grid of the audio-amplifier 166. The sockets 48 20 and 50 for receiving the plugs or tip jacks 44 and 46 are inserted into the lead 172 and are connected by a resilient contact strip 174 which is adapted to break the direct connection between the sockets 48 and 50 when the tip jacks 25 44 and 46 are inserted therein. Upon removal of the tip jacks 44 and 46, the resilient contact strip 174 automatically connects the sockets 48 and 50 and directly connects the grid of the tube 166 with the volume control resistor 168. The location of the sockets 48 and 50 between the volume control resistor and the grid of the tube 166 is of importance because such location eliminates the need of adjusting the volume control when the radio receiver is used for telephonic communication purposes.

Subsequent stages of audio-amplification are indicated as an amplifier 176. The amplifier 176 is connected in the customary manner by a transformer 178 to the input of a power amplifier 40 180, which preferably comprises a pair of power tubes 182 and 184, the grid and cathode electrodes of which are connected in conventional manner to the transformer 178 in push-pull. The output leads 186 and 188 from the plates of 45 the tubes 182 and 184, respectively, are connected to suitable plug-receiving contacts associated with the socket 42. A lead 190 connects the positive side of the B voltage supply source to one of the plug-receiving contacts of the 50 socket 42. The elements just previously described, with the exception of the plugs 48 and 50 and the resilient strip 174 connecting said plugs, comprise any usual radio receiver.

The cable 34 connecting the tip jacks 44 and 46 to the control unit preferably comprises two wires—192 and 194, the wire 192 connecting the tip jack 44 to a wire 196 connected to the movable contact 70 of the switch means 30 and the wire 194 connecting the tip jack 46 to a wire 198 60 connected to the movable contact 86. A condenser 200, of the order of $\frac{1}{1000}$ of a microfarad, is interposed in the wire 198 and a resistor 202 of the order of 100 megohms is connected between the wires 198 and 196 at a point in advance of the condenser 200.

The cable 32, which is adapted to connect the receiver socket 42 to the control unit preferably comprises three wires 204, 206 and 208, the wire 204 connecting the plate lead 186 to a wire 210 connected to the movable contact 72. The wire 206 connects the positive B supply lead 190 to a wire 212 connected to the movable contact 78 and the wire 208 connects the plate lead 188 to a wire 214 connected to the movable contact 74.

The cable 52, which connects the reproducing microphone or loud speaker 4 to the control unit, preferably comprises three wires 216, 218 and 220. The wire 216 connects one end of the primary winding of the speaker transformer 222, the secondary of which is connected to the speaker voice coil 224, to a wire 226. The wire 226 is connected to the central fixed contact 98 associated with the movable contact 72. The wire 218 connects the midpoint of the primary of the speaker transformer 222 with a wire 228, which in turn is connected to the fixed contacts 122 and 124 associated with the movable contact 78. The wire 220 connects the other end of the primary 15 of the transformer 22 with the fixed contact 144 associated with the movable contact 84.

The cable 36, connecting the remotely located reproducer-microphone or loud speaker 6 with the control unit, preferably comprises three 20 wires—232, 234 and 236, the wire 232 connecting one end of the primary winding of the speaker transformer 238 to a wire 240 connected to the fixed contact 152 associated with the movable contact 86. The wire 234 connects the midpoint 25 of the primary winding of the transformer 238 to a wire 242 connected to the fixed contacts 128 and 132 associated with the movable contact 80. The wire 236 connects the other end of the primary winding of said transformer 238 with 30 a wire 244 connected to the fixed contacts 102 and 106 associated with the movable contact 74.

Suitable interconnections are provided within the control unit and these interconnections are made as follows. A wire 246 connects the fixed 35 contacts 92 and 94 associated with the movable contact 70 with a condenser 248, the other side of the condenser being grounded as at 250. A jumper 252 connects the movable contact 76 to the ground connection at 250. A lead 254 connects the movable contact 82 with the fixed contact 118 associated with the movable contact 76. A wire 256 connects this lead with the wire 244. A jumper 258 connects the fixed contacts 120 and 138 associated with the movable contacts 76 and 45 82, respectively, and a wire 260 connects this jumper to the wire 226.

A lead 262 interconnects the fixed contacts 93 and 100 associated with the movable contact 72 with the movable contact 84 and a jumper 264 50 connects the lead 262 with the fixed contact 152 associated with the movable contact 86 and with the wire 240. A jumper 266 interconnects the lead wire 212 and the movable contact 78 with the movable contact 80. A wire 268 connects 55 the fixed contact 144 associated with the movable contact 84 with the fixed contact 154 associated with the movable contact 86 and a jumper 270 connects the wire 268 with the fixed contact 104 associated with the movable contact 74. The wire 60 272 connects the fixed contact 150 associated with the movable contact 86 to the wire 105 and the movable contact 70.

Certain of the fixed contacts, viz., the contacts 90, 116, 126, 130, 140, 142, 146 and 148 are not 65 connected to any other contact or lead, these contacts being shown in the drawings for the purpose of clarity of description and because there will be less likelihood of error in assembling the switching means 30 if all of the supporting disks, 70 108, 134 and 156, are identical and provided with identical arrangements of contacts.

Within the housing of the reproducer-microphone or loud speaker 6, the secondary of the transformer 238 is connected at one end by a wire 75 274 to the contact plate 56 of the switch 10. The

other end of the transformer is connected by wires 276 and 278 to one side of the battery 54 and to one side of the usual voice coil 280. The other side of the battery is connected to the fixed contact 64 and the other side of the voice coil is connected to the fixed contact 60.

The coil 282 of the buzzer 8 is connected between the wire 276 and the fixed contact 62, and the interrupter 284 of the buzzer 8 is connected between the movable contact 58 and the side of 10 the buzzer coil connected to the fixed contact 62.

The various circuits completed by the control unit in the three different positions of the switching means 30 are as follows. With the switch in the position shown in Fig. 3 each movable 15 contact will be in engagement with its first fixed contact. The lead 172 from the potentiometer 168 will be connected to the grid of a tube 166 through the socket 48, the tip jack 44, wires 192, 196 and 272 to the fixed contact 150 and from 20 the fixed contact 150 through the movable contact 86, a wire 198, condenser 200, wire 194, tip jack 46 and socket 50. The receiver is therefore adjusted for the passage of radio signals from the detector to the power output amplifier 180. 25

Radio signals in the output of the power amplifier 180 are transmitted to the reproducer-microphone 4, operating as a loud speaker, and to the remotely located reproducer-microphone also operating as a loud speaker. Current in the 30 output of the power amplifier 180 flows from the positive source of B voltage supply through the wires 190, 206, and 212 to the movable contact 78, and through the jumper 266 to the movable contact 80. From the movable contact 78 current passes by way of the fixed contact 122, the wire 228 and the wire 218 to the midpoint of the primary winding of the transformer 222. Current returns from the transformer 222 by wires 216, 226, 260, 258, fixed contact 138, movable contact 82, jumper 254, wire 256, fixed contact 102, movable contact 74, wire 214, wire 208 and the wire 188 to the plate of the tube 182.

Current is returned from the other side of the transformer 222 by wires 220, 230, fixed contact 45 144, movable contact 84, wire 262, fixed contact 96, movable contact 72, wire 210, wire 204 and wire 186 and the plate of the tube 182.

It will be seen therefore that radio signals in the output of the power amplifier 180 are impressed on the reproducer-microphone 4 acting as a loud speaker. The circuit to the reproducer-microphone 6 is completed from the positive side of the B supply voltage through wires 190, 206, 212, 266, movable contact 80, fixed contact 128, 50 wire 242 and wire 244 to the midpoint of the primary of the transformer 238. From one end of this primary the current is returned through wire 232, wire 240, wire 264, wire 262, fixed contact 96, movable contact 72, wire 210, wire 204 55 and wire 186 to the plate of the tube 182. From the other side of the primary of the transformer 238, the current returns through wire 236, wire 244, fixed contact 102, movable contact 74, wire 214, wire 208 and wire 188 to the plate of the 60 65 tube 184.

The secondary of the transformer 238, with the push button 68 in its normal extending position, is connected to the voice coil 280 through the wire 274, switch blade 56, fixed contact 60, the 70 voice coil 280 and the wire 278. It will therefore be seen that radio signals in the output of the power amplifier 180 will be transmitted to and impressed upon the reproducer-microphone 6 operating as a loud speaker. 75

With the switching means 30 in the position shown in Figs. 2 and 3 for the completion of the circuits just described, the push button 68 associated with the remotely positioned switch 10 5 may be operated to impress upon the speaker 4 a calling signal voltage. The push button 68, when depressed, connects the free end of the buzzer 8 to the wire 214 by means of the fixed contact 62 and the switch blade 56 and connects 10 the interrupter 284 of the buzzer 8 to the battery 54 through the fixed contact 64 and the switch blade 58. The interrupted currents provided by the buzzer 8 are therefore applied to the secondary of the transformer 238, which secondary is 15 now acting as a primary, and these currents are by induction transferred to the primary thereof and supplied to the wires 232 and 236. The current flows over the wire 232 through the wire 240, the wire 264, the movable contact 84, the fixed contact 144, the wire 230 and the wire 220 leading 20 to the speaker 4 associated with the radio receiver. Current supplied by the wire 236 passes through the wire 244, the wire 256, the wire 254, the movable contact 82, the jumper 258, the wire 250 and the wire 226 to the wire 216 leading to 25 the other side of the primary winding of the transformer 222 associated with the loud speaker 4. The buzzer 8 at the remote point thereby impresses upon the loud speaker 4 a calling signal 30 signifying that a person at the remote point desires to communicate over the system with a person at the radio receiver.

With the switching means 30 in its intermediate position, each of the movable contacts will 35 engage the intermediate fixed contact, thereby connecting the reproducer 6 at the remote point in the grid circuit of the tube 166 of the radio receiver and maintaining the reproducer-microphone 4 connected to the output power amplifier 180. These connections are accomplished as 40 follows. The wire 232 from the remote speaker is connected by the wire 240, the fixed contact 152, the movable contact 86, the wire 198, the condenser 200, the wire 194, the tip jack 46 and the socket 50 to the grid of the tube 166. The wire 236 leading from the remote point is connected by the wire 244, the wire 256, the fixed contact 118, the movable contact 76, and the wire 252 to ground at 250. The lead 172 from the 45 potentiometer 168 is connected by the socket 48, the tip jack 44, the wire 192, the wire 196, the movable contact 70, the fixed contact 92, the wire 246 and the condenser 248 to ground at 250. It will, therefore, be seen that voice current fluctuations produced in the voice coil 280 by vibration 50 of the diaphragm of the reproducing microphone 6 will be impressed upon the grid of the tube 166. The connection between the power amplifier 180 and the reproducer-microphone 4, still operating as a loud speaker, will be maintained through the wires 210, 212, and 214. The wire 210 is connected to the wire 226 leading to the speaker 4 by the movable contact 72 and the fixed contact 98; the wire 212 is connected to the wire 228 leading to the speaker 4 by the movable contact 78 and the fixed contact 124; and the wire 214 is connected to said speaker by the movable contact 74, the fixed contact 104, the wire 270 and wire 268 to the speaker wire 230 at the fixed 60 contact 144. It will therefore be seen that telephonic communication may be established between a person at the remote reproducer-microphone 6, now operating as a microphone, and a person at the reproducer-microphone 4, now operating as a loud speaker, the communication 65

being established through the audio and power amplifier of the radio receiver.

In this position of the controlling switch 30, operation of the switch 10 connects the buzzer 8 to the transformer 238 in the manner previously 5 stated and the interrupted voltage generated by the buzzer 8 is impressed in the grid circuit of the tube 166 and, by the audio and power amplifiers of the radio receiver, impressed on the speaker 4, thereby providing a signal indication that the 10 called person is present at the remote point.

When it is desired to establish telephonic communication in the opposite direction, the switching means 30 is operated to cause each of the movable contacts to engage the third of its associated fixed contacts. With the switch in this position the reproducer-microphone 4 will be connected in the grid circuit of the tube 166 and the reproducer-microphone 6 will be connected in the output of the amplifier 180. 20

These connections are established as follows: The wire 216 from the reproducer-microphone 4, now operating as a microphone, is connected by the wire 226, the wire 260, the fixed contact 120, the movable contact 76 and the wire 252 and 25 to ground at 250. The wire 220 from the speaker 4 is connected by the wire 230, the wire 268, the fixed contact 154, the movable contact 86, the wire 198, the condenser 200, the wire 194, tip jack 46, and the socket 50 to the grid of the 30 tube 166. The wire 232 from the reproducer-microphone 6, now operating as a loud speaker is connected by the wire 240, the wire 264, the wire 262, the fixed contact 100, the movable contact 72, and the wire 210 to the wire 204 35 connected by the wire 186 to the plate of the tube 182. The wire 236 from the speaker 6 is connected by the wire 244, the fixed contact 106, the movable contact 74, and the wire 214 to the wire 208 connected by the wire 188 to the plate 40 of the tube 184. The B supply voltage for operation of the tubes 182 and 184 and the speaker 6 is supplied from the lead 190 by the wire 206, the wire 212, the wire 266, the movable contact 80, the fixed contact 132, the wire 242, and the 45 wire 234 to the midpoint of the primary of the transformer 238. It will therefore be seen that in this third position of the control switch 30, telephonic communication may be established between the person at the speaker 4, now operating as a microphone, and a person at the remote reproducer-microphone, now operating as a speaker. 50

When the reproducer-microphone 4 is operating as a microphone, operation of the switch 10 55 is ineffective to impress a calling signal on said microphone, the wires 232, 234 and 236 from the speaker 6 being disconnected from the wires 226, 228 and 230 leading to the reproducer-microphone 4 at the movable contacts 72, 78 and 74. 60 This, therefore, prevents interference with the reproducer-microphone 4, when the same is operating as a microphone.

It will be evident therefore that applicant has provided an efficient means of striking simplicity 65 by which a radio receiver may be selectively controlled to transmit radio signals to a remote point and to establish two-way telephonic communication between a person at the receiver and a person at the remote point.

Changes may be made in the form, construction and arrangement of the parts without departing from the spirit of the invention or sacrificing any of its attendant advantages, and the right is hereby reserved to make all such 70 75

changes as fairly fall within the scope of the following claims.

The invention is hereby claimed as follows:

1. In combination, a radio receiver comprising a signal circuit and a reproducer, a second reproducer located at a point remote from said receiver, and a control unit for selectively connecting both of said reproducers in the output of said circuit or one of said reproducers in the output of said circuit and the other of said reproducers to an intermediate point in said circuit whereby radio or two-way telephonic communication is selectively established with the remote point by means of said radio receiver. 10
2. In combination, a radio receiver comprising a detector, an audio-amplifier and a reproducer, a second reproducer located at a point remote from said receiver and a control unit for selectively connecting both of said reproducers in the output of said amplifier and said detector to the input of said amplifier, or one of said reproducers in the output of said amplifier and the other of said reproducers in the input of said amplifier whereby radio signals may be reproduced at the receiver and at the remote point and two-way telephonic communication may be established with the remote point. 20
3. In combination, a radio receiver comprising a signal circuit and a reproducer, a second reproducer located at a point remote from said receiver and a control unit for selectively connecting both of said reproducers in the output of said signal circuit or one of said reproducers in the output of said circuit and the other of said reproducers to an intermediate point of said circuit whereby radio signals may be reproduced at the receiver and at the remote point and two-way telephonic communication may be established with the remote point, and means for transmitting a calling signal from one reproducer to the other. 30
4. In combination, a radio receiver comprising a signal circuit and a reproducer, a second reproducer located at a point remote from said receiver, and a control unit for selectively connecting both of said reproducers in the output of said circuit or one of said reproducers in the output of said circuit and the other of said reproducers to an intermediate point of said circuit whereby radio signals may be reproduced at the receiver and at the remote point and two-way telephonic communication may be established with the remote point, a call signal generator, and means associated with the remotely positioned reproducer for operatively connecting said call signal generator to the first reproducer to impress a calling signal on the first reproducer. 40
5. In combination, a radio receiver comprising a signal circuit and a reproducer, a second reproducer located at a point remote from said receiver and a control unit for selectively connecting one of said reproducers in the output of said circuit and the other of said reproducers to an intermediate point of said circuit whereby two-way telephonic communication is established with the remote point, calling means at the remote point, and means operable when the remote reproducer is connected to the intermediate point of said signal circuit for connecting said calling means to said intermediate point and operable when said remote reproducer is connected in the output of said signal circuit to connect said calling means directly to the reproducer of the receiver. 50
6. In combination with a radio receiver having a signal circuit, in the output of which is connected terminal means adapted to detachably receive the terminal means of a reproducer forming a part of the receiver, a second reproducer located at a point remote from said receiver, a control unit comprising switch means, means to connect said switch means to the output terminal means of the receiver, means to connect the switch means to an intermediate point of the signal circuit, means to connect the switch means to the reproducer of the receiver, and means to connect said switch means to the remote reproducer, said switch means being operable selectively to connect either one 15 of said reproducers in the output of said signal circuit and the other of said reproducers to the intermediate point of said signal circuit whereby two-way telephonic communication is established with the remote point. 20
7. In combination with a radio receiver having a signal circuit, in the output of which is connected terminal means adapted to detachably receive the terminal means of a reproducer forming a part of the receiver, a second reproducer located at a point remote from said receiver, a control unit comprising switch means, means to connect said switch means to the output terminal means of the receiver, means to connect the switch means to an intermediate point of the signal circuit, means to connect the switch means to the reproducer of the receiver and means to connect said switch means to the remote reproducer, said switch means being operable selectively to connect both of said reproducers in the output of said circuit or either one of said reproducers in the output of said circuit and the other of said reproducers to the intermediate point of said circuit, whereby radio signals may be simultaneously transmitted to said reproducers or two-way telephonic communication may be established with the remote point. 30
8. In combination with a radio receiver having a signal circuit in the output of which is connected terminal means adapted to detachably receive the terminal means of the reproducer forming a part of the receiver, a second reproducer located at a point remote from said receiver, a control unit comprising switch means, means to connect said switch means to the output terminal means of the receiver, means to connect the switch means to an intermediate point of the signal circuit, means to connect the switch means to the reproducer of the receiver, and means to connect said switch means to the remote reproducer, said switch means being operable selectively to connect both of said reproducers in the output of said circuit or either one of said reproducers in the output of said circuit and the other of said reproducers to the intermediate point of said circuit whereby radio signals may be simultaneously transmitted to said reproducers or two-way telephonic communication may be established with the remote point. 40
9. In combination with a radio receiver comprising an amplifier, volume control means in the input of said amplifier and a reproducer, a second reproducer located at a point remote from said receiver, and a control unit for selectively connecting both of said reproducers in the output of said signal circuit or either one of said reproducers in the input of said amplifier between 70 75

said volume control means and the input circuit of the amplifier, and the other of said reproducers in the output of said amplifier whereby radio signals may be reproduced at the receiver and at the remote point and two-way telephonic communication is established with the remote point all under the control of the volume control means of the radio receiver.

10. In combination, a radio receiver comprising a signal circuit and a reproducer, a second reproducer located at a point remote from the receiver, and a control unit for selectively connecting both of said reproducers in the output of said signal circuit or said reproducers alternately 15 to an intermediate point and to the output of said signal circuit, one of said reproducers being connected to the intermediate point when the other is connected to the output.

11. In combination, a radio receiver comprising 20 a signal circuit and a reproducer, a second reproducer located at a point remote from the receiver, and a control unit for selectively and alternately connecting said reproducers to an intermediate point and to the output of said signal circuit, one of said reproducers being connected 25 to the intermediate point when the other is connected to the output, said control unit comprising means for simultaneously connecting both of said reproducers in the output of said signal circuit for the simultaneous reproduction of radio signals at the receiver and at the remote point.

12. In combination with a radio receiver having an audio amplifier, a power amplifier, and a reproducer, a second reproducer located at a 30 point remote from said receiver, a control unit, connections from the input of the audio amplifier and from the output of the power amplifier to said control unit, connections from each of said reproducers to said control unit, said control unit comprising multi-position switch means operable 35 in one position to connect both of said reproducers to the connections from the output of the power amplifier, in another position to connect the reproducer of the receiver to the connections 40 from the output of the power amplifier and the remote reproducer to the connections from the input of the audio amplifier and said switch means being operable in a third position to connect the remote reproducer to the connections 45 from the output of the power amplifier and the reproducer of the receiver to the connections from the input of the audio amplifier.

13. In combination with a radio receiver having an audio amplifier, a power amplifier, and a 50 reproducer, a second reproducer located at a point remote from said receiver, a control unit, connections from the input of the audio amplifier and from the output of the power amplifier to said control unit, connections from each of said reproducers to said control unit, said control unit comprising multi-position switch means operable 55 in one position to connect both of said reproducers to the connections from the output of the power amplifier, in another position to connect the reproducer of the receiver to the connections 60 from the output of the power amplifier and the remote reproducer to the connections from the input of the audio amplifier and said switch means being operable in a third position to connect the remote reproducer to the connections 65 from the output of the power amplifier and the reproducer of the receiver to the connections from the input of the audio amplifier, and signalling means at the remote point adapted to transmit 70 over the connections from the remote reproducer 75

to the control unit a calling signal which is impressed by said control unit on the reproducer of the receiver.

14. In combination with a radio receiver having an audio amplifier, a power amplifier, and a 5 reproducer, a second reproducer located at a point remote from said receiver, a control unit, connections from the input of the audio amplifier and from the output of the power amplifier to said control unit, said control unit comprising 10 multi-position switch means operable in one position to connect both of said reproducers to the connections from the output of the power amplifier, in another position to connect the reproducer of the receiver to the connections from the output 15 of the power amplifier and the remote reproducer to the connections from the input of the audio amplifier and said switch means being operable in a third position to connect the remote reproducer to the connections from the output of the power amplifier and the reproducer of the receiver to the connections from the input of the audio amplifier, and means for normally urging 20 said switch means to its first position wherein both of said reproducers are connected to the output of the power amplifier.

15. In combination, a radio receiver comprising an audio amplifier, a power amplifier and a reproducer, said audio amplifier comprising a thermionic tube having a controlling grid and 30 volume control means connected to said grid, a second reproducer located at a point remote from the receiver, a control unit, connections from the control unit to the audio amplifier at a point 35 between the volume control means and the controlling grid of the thermionic tube, connections from the output of the power amplifier to said control unit, connections from each of said reproducers to said control unit, said control unit comprising multi-position switch means operable 40 in one position to connect both of said reproducers to the output of the power amplifier, in another position to connect the reproducer of the receiver to the output of the power amplifier and the remote reproducer to the controlling 45 grid of the thermionic tube, and said switch means being operable in a third position to connect the remote reproducer to the output of the power amplifier and the reproducer of the receiver to the controlling grid of the thermionic 50 tube.

16. In combination, a radio receiver comprising an audio amplifier, a power amplifier and a reproducer, said audio amplifier comprising a thermionic tube having a controlling grid and 55 volume control means connected to said grid, a second reproducer located at a point remote from the receiver, a control unit, connections from the control unit to the audio amplifier at a point between the volume control means and the controlling grid of the thermionic tube, connections from the output of the power amplifier to said control unit, connections from each of said reproducers to said control unit, said control unit comprising multi-position switch means operable 60 in one position to connect both of said reproducers to the output of the power amplifier, in another position to connect the reproducer of the receiver to the output of the power amplifier and the remote reproducer to the controlling grid of 65 the thermionic tube, and said switch means being operable in a third position to connect the remote reproducer to the output of the power amplifier and the reproducer of the receiver to the controlling grid of the thermionic tube, said 70 75

control unit comprising means for disconnecting the volume control means from the controlling grid of the thermionic tube when either of said reproducers is connected to said controlling grid.

5 17. A control unit for connecting a radio receiver, comprising a detector, an audio-amplifier, and a reproducer, having a connecting plug normally received in an output socket of the audio-amplifier, to an additional remotely located reproducer selectively to provide simultaneous reproduction of radio signals at distant points and two-way telephonic communication between said distant points, said unit comprising a three-position switch means, means connecting said switch means to a point between the detector and audio-amplifier of the radio receiver, a socket for receiving the plug of the reproducer of the receiver, said socket being connected to said switch means, means including a plug for connecting said switch means to the output socket of the audio-amplifier of the receiver and means connecting said switch means to the additional remotely located reproducer, said switch means including contacts adapted selectively to connect both of said reproducers to the output socket of the audio-amplifier or either one of said reproducers to the output socket of the audio-amplifier and the other of said reproducers to the point between the detector and audio-amplifier whereby radio signals may be simultaneously transmitted to said reproducers or two-way telephonic communication may be established between the receiver and the remotely located reproducer.

18. In combination with a radio receiver having an audio amplifier, a power amplifier, and a reproducer, a second reproducer located at a point remote from said receiver, a control unit, connections from the input of the audio amplifier and from the output of the power amplifier to said control unit, connections from each of said reproducers to said control unit, said control unit comprising multi-position switch means operable in one position to connect both of said reproducers to the connections from the output of the power amplifier, in another position to connect the reproducer of the receiver to the connections from the output of the power amplifier and the remote reproducer to the connections from the input of the audio amplifier and said switch means being operable in a third position to connect the remote reproducer to the connections from the output of the power amplifier and the reproducer of the receiver to the connections from the input of the audio amplifier, a call signal generator, means associated with the remotely positioned reproducer including connections to said multi-position switch means for operatively connecting said call signal generator to the reproducer of the receiver when said multi-position switch means is in its first or second position, said connections being broken by said multi-position switch means when in its third position to prevent impression of a call signal on the reproducer of the receiver when connected to the input of the audio amplifier.

WILLIAM J. SCHINELL.
